(57) **CLAIM**

The ornamental design for a mat, as shown and described.

DESCRIPTION

FIG. 1 is an upper perspective view of a mat showing my new design.

FIG. 2 is a rear view thereof;

FIG. 3 is a front view thereof;

FIG. 4 is a right side view of the mat, a left side view being a mirror image thereof;

FIG. 5 is a top view of the mat; and,

FIG. 6 is a close-up view of the encircled area from FIG. 4.

1 Claim, 4 Drawing Sheets

FIG. 1

FIG. 2

FIG. 3

FIG. 4

FIG. 5

FIG. 6
